LAWRENCE V. FEIKE AND JAMES R. PAYTON, OF DES MOINES, IOWA.

WAX ELIMINATOR.

Application filed February 3, 1926. Serial No. 85,660.

The object of this invention is to provide a convenient electrically heated device in which a dentist's mold may be placed and heat applied for the purpose of melting and eliminating the wax pattern and also for thoroughly drying the plastic material of the mold to prepare it for making a cast.

A further object of this invention is to provide improved means for eliminating a fusible pattern from a small mold such as used by dentists, means being provided for determining and regulating the degree of heat to be applied.

A further object of this invention is to provide an improved electrical heating device or stove especially adapted for use by dentists in making ready for the cast the molds which are used for producing inlays, crowns and the like, and also convenient for use in sterilizing instruments.

Still a further object is to provide an improved construction for an electrical heating device of the character described.

With these and other objects in view, our invention consists in the construction, arrangement and combination of elements hereinafter set forth, pointed out in the claim and illustrated by the accompanying drawing, in which—

30 Figure 1 is a plan view, partly in section, of our improved device.

Figure 2 is a side elevation of the same, also partially in section.

Figure 3 is a detail elevation on the line 35 3—3 of Figure 1, showing a mold in position for use in and treatment by the device.

Figure 4 is an elevation, partly in section, illustrating an accessory which may be used with the device for the purpose of sterilizing 40 instruments and the like.

Figure 5 is a diagram of the electrical connections employed in the heater.

In the construction of the device as shown the numeral 10 designates a base which may 45 be of any suitable insulating material. On the base 10 is mounted and secured a housing which is preferably cylindrical, and is composed of an inner wall 11 having an integral bottom 12 which rests on the base 10. Concentric with the inner wall 11 is an outer 50 wall 13 formed at its lower margin with an outturned flange 14 resting on and secured to the base. The walls 11 and 13 are spaced apart to form an air space between 55 them, and at its upper margin the outer wall 13 is formed with an inturned flange

15 which extends across the top of the air space and inwardly of the top margin of the inner wall 11, leaving a circular opening at the top of the housing which is closable 60 by a cover 16 resting on said flange 15. A lining 17 of sheet asbestos or similar heat-insulating material preferably is mounted in the air space between the walls and in contact with the outer wall 13, and said lining also is extended inwardly at its top beneath the flange 15. A packing 18 of corrugated sheet asbestos or the like may be mounted in and partially fill the air space 65 between the walls if desired.

Conductor wires 19 and 20 lead to the base 10 and are adapted to be placed in circuit in a common manner through an ordinary lamp socket or wall opening connected with a source of electrical energy. In circuit with the lead wires 19 and 20 are resistance wires 21 which preferably are arranged circumferentially within the housing and substantially from bottom to top 70 thereof, and supported as by insulating beads 22 carried by the inner wall 11, to supply heat to the housing when the current is on. Preferably the resistance wires 21 are arranged in series as indicated in Figure 5 and spaced contact points 23 and 24 are provided 75 adapted for selective engagement by a controlling switch 25 mounted on the base. The point 23 is isolated and not in circuit and ordinarily, when a low heat is desired, the switch is placed on it for convenience and 80 the current flows through all the resistance elements; but when a higher heat is desired the switch is placed on the point 24 so that a portion of the resistance is cut out of the circuit. At times, also, it is desirable 85 to have means for automatically cutting off the current when certain temperatures have been reached, and for this purpose a thermostat of common form, designated at 26, is provided, mounted in a recess 27 in the base. 100 A contact point 28 is in circuit with the thermostat and is engageable by the switch 25 at times, and the degree of heat at which the thermostat will operate may be adjusted and determined by an adjusting screw 29 on 105 the base. A thermometer 30 of common form may be mounted on the housing to enable the operator to determine at any time the degree of heat.

This device is especially designed for use 110 in eliminating the wax or other fusible patterns from a mold in the process of produc-

ing inlays, crowns or other small castings. For making such castings it has been customary to use a mold of suitable plastic material such as is designated by the numeral 31 in Figure 3. After the impression has been taken a wax or similar fusible pattern 32 is constructed, which is imbedded in the plastic of the mold 31, which may be supported by a metallic band 33. The mold 31 is formed with a conical mouth 34 and a duct 35 leads from said mouth to the location of the pattern 32. In using our improved device, the mold containing the pattern is placed in inverted position within the housing, as shown in Figure 3, the cover 16 is placed in position and the current turned on. The heat thus generated acts to melt and drive off the wax or other material of the pattern 32, the melted substance passing 20 through the duct 35 and through holes 36 formed in the bottom 12 of the housing and also through a hole or holes 37 in the base 10, which preferably is slightly elevated from the bench or table by knobs or the like 25 38 on its under surface. The heat also acts to thoroughly and rapidly dry out the plastic of the mold to leave it in proper condition for receiving the cast. When this is done the mold is removed and the cast made 30 by pouring molten metal into the mouth 34, it passing to the mold cavity by means of the duct 35, in the ordinary manner. It is to be understood that the construction of the mold and its method of use have nothing to do 35 with our present invention, but the illustration and description thereof are inserted here simply to make clear the method and purpose of our electrical eliminating device.

This device provides a very convenient 40 and efficient means for accomplishing this purpose, as will readily be understood by those skilled in the art.

This electrical heating device may also be 45 used for another purpose, that of sterilizing instruments and other small objects. For

this purpose we have provided an accessory shown in Figure 4, comprising a sterilizing can 39 provided with a removable cover 40. This can preferably is of greater depth than the housing and is adapted to be placed 50 therein so that its contents may be subjected to any desired degree of heat for sterilizing them. A small bucket 41, having perforations 42 in its wall, may be mounted loosely in the sterilizing can 39 to contain very small 55 objects to be sterilized, and it is provided with a bail handle 43 or other suitable means for handling it.

The cover 16 of the housing may be provided with ventilating ports 44, through 60 which a circulation of air is permitted because of the elevation of the base by the knobs 38, and the presence of the hole 37 in the base and the holes 36 in the bottom 65 of the housing.

It is to be understood that various changes and modifications are possible in the arrangement and construction of the various parts of the device, without departing from our invention as defined within the scope of the 70 appended claim.

We claim as our invention—

A device for eliminating fusible patterns from dental molds and the like, comprising a base and a housing mounted thereon, said housing including an inner wall having a bottom resting on said base, an outer wall spaced from the inner wall to form an air space therebetween, said outer wall being formed at its top with an inwardly extending flange projecting across and closing the air space and extending inwardly of the top margin of the inner wall and its inner margin forming an opening for access to the housing, and a removable cover adapted to be mounted on said flange to close said access opening.
